SIGNALING SYSTEM

Dudley E. Foster, Evanston, Ill., assignor, by
mesne assignments, to Reconstruction Finance
Corporation, Chicago, Ill., a corporation

Application June 2, 1934, Serial No. 728,699

5 Claims. (Cl. 250—20)

My invention relates in general to electronics and has more particular reference to electron flow control by means of negative bias in an electron flow circuit, the invention having particular application in the automatic control of sensitivity in electrical transfer systems, more especially radio receivers.

An important object is to provide, in an electron flow circuit, means for normally establishing an electron flow of constant character and for varying the electron flow in response to variations in strength of an electrical potential impressed upon the circuit, a further object being to accomplish the control automatically and a still further object being to provide for electron flow control only after the impressed potential exceeds a predetermined value.

Another object is to utilize a power source for normally applying a bias upon an electron flow circuit so as to induce, normally, an electron flow of substantially constant character in said circuit and to utilize the same power source to provide for automatic control of the electron flow whereby to maintain constant the energy output of the system in response to energy delivered to the system at a varying rate.

Another object is to provide an electrical transfer system, more especially a radio receiver, having means normally operable to cause the system to deliver a signal, corresponding in strength to the strength of a signal applied in the system, and also operable, after the strength of the applied signal exceeds a predetermined value, to automatically control the system, in accordance with the instantaneous amount of energy delivered thereto, so that the system may deliver energy at a uniform rate even though the amount of energy delivered to the system may fluctuate; a further object being to accomplish the foregoing by biasing the transfer circuit and more particularly by a normal or initial bias of constant character and a delayed bias of fluctuating character, and to produce both the initial bias and the delayed, or automatic electron flow control, bias from a common source of biasing potential.

Among the other important objects and advantages of my present invention is to utilize an electron flow device such as a diode to produce, for biasing purposes, unidirectional potential fluctuating in proportion to the strength of a signal impressed upon said system and to apply said potential to variably bias an amplifier forming a part of said system and thus control signal amplification; to utilize an initial bias of substantially constant value to delay the application

of the fluctuating bias until the strength of the impressed signal exceeds a predetermined value; to maintain at substantially uniform strength, signals, delivered to an electrical signal transfer system, such as a radio receiver; to prevent application, to the amplifier, of undesired vibrations developed by the detector action of the diode, or other device used for developing the variable bias, and to accomplish the foregoing specifically by applying the biasing potential to the amplifier through a filter designed to eliminate the undesirable frequency fluctuations in the biasing potential; to accomplish filtration by applying the biasing potential through a biasing circuit including a condenser adapted to maintain its charge substantially at peak value during any vibration of the frequency order which it is desired to exclude; to control the bias applied to the amplifier of a signal transfer system, such as a radio receiver, in proportion to variations in the energy of the applied signal as, for example, during fading; to arrange the condenser, which accomplishes the control during fading, so as to maintain its charge during vibrations having higher than the fading frequency accommodated and thus prevent alteration of the bias applied to the amplifier in response to normal audio or radio frequency components of the applied signal; to arrange the alternating current and fading frequency control means in cascade form when applying the same in a system having more than one stage of amplification so that the filtering action on the biasing potential applied to an earlier stage of amplification will be greater than that on the biasing potential applied to a later stage in order to provide a filtration safety factor for the biasing potential applied to the initial amplifying stages, to separate the stages and prevent inter-action therebetween; and to improve the operation of the bias-applying circuit in response to fading; to utilize, in a signal transfer system, a condenser, in parallel relationship with an electron flow device, such as a diode, operating as a detector, and so proportioned that the voltage developed across the resistance, by the operation of the electron flow detector, will be maintained substantially constant during a relatively high frequency or super audio vibration, the resistance and condenser, however, being proportioned to permit discharge of the condenser and consequent reduction of the voltage developed across the resistance during any relatively low frequency vibration so as to vary the potential across the resistor in accordance with the fluctuations in

the low frequency vibrations impressed thereon to permit the circuit to function as a detector; to utilize capacity reactance in combination with an electron flow device, in a translation system, 5 to detect a component of predetermined frequency in a modulated or composite wave impressed upon the system; to detect a component of predetermined frequency in a composite wave containing said component by controlling the 10 potential developed in an electron flow device on which the composite wave is impressed.

These and numerous other objects, advantages, and inherent functions of the invention will become apparent as the same is more fully understood from the following description, which, taken 15 in connection with the accompanying drawing, discloses signal transfer systems embodying my invention.

Referring to the drawing:

20 Figure 1 is a diagrammatic representation of a signal transfer system embodying my present invention.

Figure 2 is a diagrammatic view showing how 25 resistance and capacity in the bias-applying circuit may be arranged in cascade in order to afford a greater filtering effect upon the biasing potential applied to an early stage of amplification than upon the biasing potential applied to a later stage.

30 Figure 3 is a diagrammatic view showing the electron flow device, which develops the biasing potential, connected in the system substantially in advance of the detector in order to preserve the apparent selectivity of the system.

35 Figure 4 shows how the detector and bias potential producing elements may be combined.

To illustrate my invention, I have shown a 40 signal transfer system comprising a plurality of electron flow devices including an initial amplifier element 11, a second amplifier element 13, a detector element 15, a bias potential developing element 17, and means interconnecting said elements to form a signal transfer system.

Each of the elements 11, 13, 15, and 17 45 comprises an electron emitting device or cathode 19, which, in the illustrated embodiment, comprises a filament. The filaments may be energized for electron emission in any suitable fashion, as by connecting the same with a source of electrical power. The cathodes 19 also are preferably grounded, which, as shown in Figure 1, is accomplished by connecting the same to a common 50 grounded conductor 21. Each of the elements 11, 13, 15, 17, respectively, has a plate or anode 12, 14, 16, and 18, and the amplifying elements 11 and 13 are also provided each respectively with grids 23 and 25 to which negative bias may be applied in accordance with the teaching of my 55 present invention. The amplifier elements 11 and 13 may be coupled together and to the detector element 15 and to the antenna or signal-receiving element 27 in any suitable fashion, but I have, for the sake of illustrating my invention, shown coupling means comprising transformers 60 28, 29, and 30, which are shown as radio frequency transformers, since the amplifiers 11 and 13, in the illustrated embodiment, are radio frequency amplifiers. It will, however, be understood that the principles of the invention are not 65 necessarily restricted to radio frequency amplification.

To apply the signal to the transfer system, the antenna 27 is connected to one end of the primary winding 31 of the transformer 28, the opposite end of which primary winding is grounded. 70

One end of the secondary winding 33 of the transformer 28 is connected to the grid 23 of the initial amplifier element 11, the opposite end of said secondary winding being connected through a resistance 35 and a resistance 37 to the negative side of a direct current power source 39, the positive side of which is connected to the grounded conductor 21. A tuning condenser 41 is preferably connected between the opposite ends of the secondary winding 33. 10

The plate 12 of the element 11 is connected to one end of the primary 51 of the transformer 29, the opposite end of said primary winding being connected through suitable direct current, plate potential, power source and thence back to the 15 cathode of the amplifier element 11. One end of the secondary winding 53 of the transformer 29 is connected with the grid 25 of the second amplifier element 13, the opposite end of said secondary winding being connected through the resistance 55 and the resistance 37 to the negative side of the power source 39. A tuning condenser 61 is preferably connected between the opposite ends of the secondary winding 53. The circuits, from the power source 39, to the grids of the 20 amplifier elements 11 and 13, through the resistor 35 and the control resistor 37, comprise bias potential applying circuits, and a condenser 63 is connected between the grounded conductor 21 and these potential-applying circuits, at a 25 point between the resistor 35 and said grids, for a purpose hereinafter more fully explained.

The plate 14 of the second amplifier element 13 is connected to one side of the primary winding 71 of the transformer 30, the opposite end of said primary winding being connected through a suitable direct current, plate potential, power source, and thence back to the cathode of the amplifier element 13. The secondary winding 73 of the transformer 30 forms the input to a detecting circuit, one end of said winding being connected to the plate 16 of the detector element 15, the opposite end of said secondary winding 73 being connected to the grounded conductor 21 through a resistance-capacity net work 75 comprising a 30 resistor 77 and condenser 79 arranged in parallel relationship. A tuning condenser 81 is connected between the opposed ends of the secondary winding 73, and an output connection 83 is provided in the detecting circuit between the secondary winding and the net work 75. The secondary winding 73 and its associated condenser 81, the net work 75 and the element 15 are thus associated to form a detector circuit, the function of which I shall hereinafter develop more fully. 35

The plate 18 of the automatic bias potential developing unit 17 is or may be connected through a condenser 55 to the detector circuit anywhere between the plate 16 of the detector element 15 and the winding 73. The plate 18 of the unit 17 is also connected by means of a conductor 57 through the resistor 37 to the negative side of the power source 39, so that the unit 17 is also connected to the potential applying circuit which extends to the grids of the amplifier elements. 40

A signal, impressed on the antenna, is transferred progressively through the amplifiers 11 and 13, it being understood that any number of amplifier units or stages may be utilized, the signal 45 passing to the detecting circuit through the transformer 30, and the detected signal is transferred to the output through the terminal 83.

The function of the net work 75 is to provide for 50 automatically biasing the detector element 15, 75

when the signal system is functioning, in order to maintain a constant operating potential between its anode and cathode. To this end, the resistance 11 and condenser 79 are proportioned so that the condenser will not discharge through the resistor to any great extent during any radio frequency cycle in order thus to maintain the voltage across the resistance 11 substantially at its peak value as long as the detecting circuit is subjected to radio frequency impulses, such as the carrier wave of a signal, impressed on the circuit through the transformer 30, whereby to maintain a constant operating potential across the resistance 11 during the time of the cycle of a radio frequency wave impressed on the circuit. The condenser 79, however, is arranged to discharge substantially completely during the time of the cycle of an audio frequency component of the wave impressed on the net work so that the voltage across the resistance 11 will follow the variations of the audio component of the signal, and will thus accomplish diode detection substantially without distortion.

the resistors 37 and 35 whereby a negative potential, the amount of which depends upon the voltage available at the power source and the amount of resistance supplied by the resistors 35 and 31, is applied to the grids. The arrangement also provides for the delayed application of the automatic sensitivity control effect, which becomes effective only after the strength of the signal delivered at the output reaches the full volume at which the system is designed to operate. The power source 39 is so connected that a negative potential is applied to the plate of the element 17 through the resistor 37, and until the signal reaches a strength sufficient to establish a negative condition at the plate in excess of that applied by the power source, the bias applied on the grids of the amplifiers will remain constant at the value determined by the power source. It is only after the strength of the signal increases sufficiently to develop a negative condition at the plate greater than that afforded by the power source, that the bias on the amplifier grids commences to vary in order to accomplish automatic volume control.

25 One of the objects of my present invention is to provide for increasing the amplification, accomplished upon the signal by the elements 11 and 13, inversely in proportion to the strength of the signal impressed upon the system at the antenna. This is accomplished by means of the 30 potential developing element 17, the power source 39 and resistance 37 and the connections extending through the resistance 35 to the grids 23 and 25 of the elements 11 and 13.

Order to accomplish automatic volume control. As the signal strength increases above that necessary to make the plate of the element 17 more negative than the power source 39, the remote end 25 of the resistor 37 and therefore the grids of the amplifier elements 11 and 13 will become more negative with respect to ground. Consequently, the negative bias applied to the grids will increase 30 as the signal strength increases, and the amplifying efficiency of the elements 11 and 13 will be decreased in proportion to the increase in signal

It will be noted that the anode and cathode of the element 17 are in a potential developing circuit including, in series, the resistor 37, the direct current source 39, and the conductors 21 and 57. The plate or anode 18 of the element 17 also is connected through the condenser 55 to the detector circuit. Consequently, the signal applied to the detector circuit is also applied to the element 17. The application of the signal in this manner to the plate of the element 17 permits various currents to flow in the potential developing circuit and the voltage across the resistor 37, due to these currents, includes a direct current voltage proportional to the signal strength, an alternating current voltage corresponding to the audio modulation of the carrier wave of the signal 35 40 45 50 55 50 and an alternating current voltage corresponding to the carrier wave itself. The direction of the direct current component is such that the end of the resistor 37, remote from the power source 39, tends to become negative with respect to its end which is connected to the power source. The negative condition of the remote end of the resistor 37 increases with increase in signal strength impressed upon the system. Since the grids of the amplifier elements 11 and 13 are connected 55 to the remote or negative end of the resistor 37, it will be seen that the grids are at the same negative potential with respect to ground as is said remote negative end of the resistor 37. The resistor 35, which is in series with the grids does not 60 affect this condition, and the condenser 59 normally prevents any direct current from passing 65 to ground, with consequent loss of biasing potential at the grids.

50 55 60 65 60 65

It is desirable to prevent all of the alternating current potential components, developed in the element 17, from reaching the grids of the amplifiers 11 and 13. If a radio frequency component is permitted to reach the amplifier grids, the entire system will be caused to oscillate and if an audio frequency component reaches the grids, the strength of the signal delivered at the output of the system may be caused to fluctuate at audio frequency which, of course, is undesirable. I prevent these alternating current components from reaching the amplifier grids by means of the resistance 35 and the condenser 59, which cooperate to form a filter to remove the undesired components. The resistor 35 and the condenser 59 are so proportioned that the condenser will not discharge during an audio or radio frequency cycle, but will maintain the voltage applied to the grids constant during such an interval. The con-

50 55 60 65 60 65

It will be noted that my invention provides for the application of uniform negative bias on the amplifier tubes during the interval while signal strength is increasing, as during tuning of the set, to the point where automatic control is needed. This initial negative bias is accomplished directly by the power source 39 operating through condenser 59 and resistance 35, however, are proportioned so that the former will discharge during fading, which causes the applied bias potential to vary during fading to the end so that amplification will be varied in accordance with fading so as to maintain the signal strength at the output during such intervals without distortion. 70 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 As shown in Figure 2, it is within the contemplation of my present invention to divide the resistor 35 into two parts 34 and 36 so that the biasing potential delivered to the grid of the initial amplifier element 11 must pass through both resistor sections 34 and 36 while the bias potential applied to the grid of the amplifier element 13 passes only through the resistor section 34. In this arrangement also the function of the condenser 59 is accomplished by means of two condensers 60, one of which is connected between ground and the grid circuit of the element 11, while the other is connected between ground and the grid circuit of the element 13. I thus divide the resistance 35 and condenser 59 into a cascade arrangement in order to vary the alternating current filtration accomplished upon the biasing potential delivered to the several amplification elements to the end that the filtering effect performed upon the biasing potential delivered to the initial element 11 will be greater than the filtration accomplished upon the biasing potential delivered to the other amplifier element 13. This is desirable since permissible distortion in the initial amplifying element is much less than the permissible distortion in the other elements, since a given distortion in the initial amplifier is amplified to a greater degree and results in greater distortion in the signal delivered at the output than is the case when a similar degree of distortion occurs in the later amplifier.

Another advantage derived from cascading the resistance 35 and condenser 59 resides in the separation of the amplification stages, thus accomplished, which prevents inter-action between the stages. The cascade arrangement also affords more accurate and sensitive response to fading in the system since the condensers 60 may be selected to discharge with greater accuracy during fading than can the single condenser 59 arranged to serve a plurality of amplifier elements. By the same token, the cascade arrangement of resistance and capacity in the grid biasing circuit may be arranged to differentiate more exactly between the attenuation applied in filtering the audio and radio frequency components delivered by the element 17 at the remote end of the resistor 37 and the preservation of voltage desired during fading.

By connecting the plate of the potential generating element 17 through the condenser 55 to the detecting circuit, the relative selectivity of the detector and automatic volume control diodes is made more uniform, which makes it more difficult to tune the set properly to the carrier frequency of an applied signal. During tuning, the signal strength does not abruptly increase to its maximum value as the system reaches tuned condition, but the signal strength increases gradually to a maximum so that it is difficult to determine exactly when the system is properly tuned. This is because the automatic sensitivity control causes the grid bias to vary in accordance with signal strength in such a way as to tend to keep the output uniform. The grid bias, in the system shown in Figure 1, is proportioned to the signal strength in the detector circuit. Consequently, the output energy of the detector circuit is made more uniform not only during the operation of the system in tuned condition, but also during tuning. By connecting the plate 18 of the element 17 through the condenser 55 to a point in the amplifying system by means of a conductor 20 as shown in Figure 3, instead of to the detecting circuit, as shown in Figure 1, the selectivity of the detector

circuit may be utilized to improve the apparent selectivity of the system during tuning without impairing the automatic control features, since, by so connecting the element 17, the selectivity of the detecting circuit may be preserved unaffected by the automatic volume control action for use in tuning, which is not the case where the element 17 is connected directly to the detector circuit.

It is also possible to combine the elements 15 and 17 as shown in Figure 4 by providing a single element 63 having a filament or cathode 19 and two anodes or plates, one 16 of which is connected in the detector circuit to perform the functions of the plate of the detector unit, while the other 18 is connected through the resistor 37 to the negative side of the power source 39 and serving the function of the biasing potential generating element 17, said plate 18 being also connected through a condenser 55 either to the detector circuit or to one of the earlier amplifier stages, as indicated in dotted lines in Figure 4.

It is thought that the invention and numerous of its attendant advantages will be understood from the foregoing description, and it is obvious that numerous changes may be made in the form, construction, and arrangement of the several parts without departing from the spirit or scope of my invention or sacrificing any of its attendant advantages, the forms herein described being preferred embodiments for the purpose of illustrating my invention.

Having thus described my invention, what I claim as new and desire to secure by Letters Patent is as follows:

1. A signal transfer system comprising signal input and output means, an electron flow device including a control element and control means for developing a fluctuating biasing potential proportional to the strength of the signal impressed on the system through said input means, and for applying said fluctuating potential upon the control element in order to maintain the signal, delivered at the output means, at substantially constant strength regardless of fluctuations in signal strength applied to the system through the input means, said control means comprising a constant potential source of electrical energy connected to apply a substantially constant biasing potential on the control element, a detector element operatively associated with said transfer system and capable of developing a negative potential of magnitude corresponding to the signal strength impressed on said system through said input means, said detector element being connected with said control element in parallel with respect to said constant potential source.

2. A signal transfer system comprising signal input and output means and an electron flow device including a control element, a detector device operatively associated with said transfer system and adapted to develop a fluctuating negative potential instantaneously proportional to the signal strength applied to the system through said input means, means for applying said developed potential to the control element of the electron flow device, whereby to maintain the signal, delivered at the output, at substantially constant strength regardless of fluctuations in the strength of the signal applied to the system, and a source of electrical negative potential connected to the control element to apply a constant negative bias of predetermined value on the control element, said detector means and said power source being

connected together in parallel whereby a constant bias will be applied on said control element as long as the fluctuating potential developed by the detector means has a value less than that maintained on the control element by said source, said fluctuating developed potential becoming effective as an automatic control on said control element only after the developed potential exceeds that maintained on the control element by said power source.

3. A signal transfer system comprising signal input and output means, and a plurality of electron flow devices each having a control element and the several electron flow devices being connected in cascade arrangement between the input and output means to form successive stages of amplification in said system, means operatively associated with said transfer system for developing a fluctuating biasing potential instantaneous-
ly proportional to the signal strength impressed on the system through said input means, a source of constant biasing potential connected in parallel with respect to the potential developing means, and circuit means to apply the developed fluctuating potential and the constant potential together on the control elements of the several electron flow devices whereby a constant bias is normally applied on said control elements as long as the fluctuating potential is lower than that applied by said source, the fluctuating bias being applied only after the developed potential exceeds that provided by said source.

4. A signal transfer system comprising signal input and output means, and a plurality of electron flow devices each having a control element and the several electron flow devices being connected in cascade arrangement between the input and output means to form successive stages of amplification in said system, means operatively associated with said transfer system for developing a fluctuating biasing potential instantaneous-
ly proportional to the signal strength impressed on the system through said input means, a source of constant biasing potential connected in parallel with respect to the potential developing means, and circuit means to apply the developed fluctuating potential and the constant potential together on the control elements of the several electron flow devices whereby a constant

bias is normally applied on said control elements as long as the fluctuating potential is lower than that applied by said source, the fluctuating bias being applied only after the developed potential exceeds that provided by said source, the bias being applied on said control elements through individual bias applying circuits in relatively parallel arrangement and differential filtering means in the several bias applying circuits whereby the potential applied to one of said elements is subjected to a greater degree of filtration than is applied to the potential delivered to another of the control elements.

5. A signal transfer system comprising signal input and output means, and a plurality of electron flow devices each having a control element and the several electron flow devices being connected in cascade arrangement between the input and output means to form successive stages of amplification in said system, means operatively associated with said transfer system for developing a fluctuating biasing potential instantaneous-
ly proportional to the signal strength impressed on the system through said input means, a source of constant biasing potential connected in parallel with respect to the potential developing means, and circuit means to apply the developed fluctuating potential and the constant potential together on the control elements of the several electron flow devices whereby a constant bias is normally applied on said control elements as long as the fluctuating potential is lower than that applied by said source, the fluctuating bias being applied only after the developed potential exceeds that provided by said source, the bias being applied on said control elements through individual bias-
applying circuits in relatively parallel arrangement and differential filtering means in the several bias applying circuits whereby the potential applied to the control element of an electron flow device, comprising an advance stage of amplification, is subjected to a relatively greater degree of filtration than is applied to the biasing potential delivered on the control element of an electron flow device comprising a later amplification stage of said system.
